UNITED STATES PATENT OFFICE.

WILLIAM J. KEEP, OF DETROIT, MICHIGAN, ASSIGNOR TO THE LAMSON & SESSIONS COMPANY, OF CLEVELAND, OHIO.

DESIGN FOR A NUT FOR MICA-FRAME BOLTS.

SPECIFICATION forming part of Design No. 19,645, dated February 11, 1890.

Application filed December 9, 1889. Serial No. 333,150. Term of patent 14 years.

To all whom it may concern:

- Be it known that I, WILLIAM J. KEEP, a citizen of the United States, residing at Detroit, in the county of Wayne and State of Michigan, have invented and produced a new and original Design for Nuts for Mica-Frame Bolts, of which the following is a specification, reference being had to the accompanying drawings, forming part thereof.
- Figure 1 is a front elevation of a nut showing my design in one style of nut. Fig. 2 is a side elevation of the same, and Figs. 3 and 4 are corresponding views of the same in another style of nut.
- The leading feature of my design consists in the rounded front face of the nut ornamented by a series of radial beads extending from the center portion of the nut to the angular edge at its base.
- The base *a* of the nut is flat on its broad side and thin at its edges, the edges having an angular contour—as, for instance, hexago-

nal, as shown in Figs. 1 and 2, or square, as shown in Figs. 3 and 4. The front face *b* is rounded from its base to the center, so as to have a contour in side view of a flattened semicircle. This face is ornamented by a series of radial beads 5 extending over the entire front face, the effect of the rounded front face and beads being to break up the angular contour of the base and give the nut the appearance of one that is not specially adapted to receive a wrench.

What I claim is—

The design for a nut for mica-frame bolts herein shown and described, the same comprising the contour of the angular base, the rounded front face of a flattened semicircular contour in side view, and the series of radiating beads on the front face, as set forth. 40

WILLIAM J. KEEP.
